CLAIM

We claim the ornamental design for a case for mobile phone, as shown and described.

DESCRIPTION

FIG. 1 is a front, left and bottom perspective view of a case for mobile phone showing our new design;

FIG. 2 a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front, left and top perspective view thereof showing the ring stand feature of the case for mobile phone in an open state.

The broken lines depict portions of the case for mobile phone that form no part of the claimed design.

1 Claim, 9 Drawing Sheets
